CARD FILE CABINET

Peter J. Protzmann, Grand Rapids, Mich., assignor to Herman Miller Inc., Zeeland, Mich., a corporation of Michigan

Filed Oct. 18, 1968, Ser. No. 14,066

Term of patent 14 years

Int. Cl. D6—01

U.S. Cl. D33—19

FIG. 1

FIG. 2.

FIG. 3.

FIG. 5.

FIG. 4.

FIG. 1 is a perspective view of the card file cabinet;
FIG. 2 is a front elevation thereof;
FIG. 3 is a side elevation thereof;
FIG. 4 is a plan view thereof; and
FIG. 5 is a rear elevation thereof.

The side opposite that shown in FIG. 3 is a mirror image of that shown in FIG. 3.

I claim:

The ornamental design for a card file cabinet, substantially as shown and described.
